UNITED STATES PATENT OFFICE.

CHARLES J. KLEIN, OF MILWAUKEE, WISCONSIN, ASSIGNOR TO THE CUTLER-HAMMER MFG. CO., OF MILWAUKEE, WISCONSIN, A CORPORATION OF WISCONSIN.

ELECTRIC SWITCH.

1,313,701.

Specification of Letters Patent.

Patented Aug. 19, 1919.

Application filed July 3, 1914. Serial No. 848,754.

To all whom it may concern:

Be it known that I, CHARLES J. KLEIN, a citizen of the United States, residing at Milwaukee, in the county of Milwaukee and 5 State of Wisconsin, have invented new and useful Improvements in Electric Switches, of which the following is a full, clear, concise, and exact description, reference being had to the accompanying drawing, forming 10 a part of this specification.

This invention relates to electric switches.

One of the objects of the invention is to provide a cheap and efficient snap switch mechanism particularly adapted for flush 15 switches.

A further object is to provide an improved switch mechanism of the character set forth which embodies, in combination, various novel and advantageous features.

20 In order that the invention may be more readily comprehended, I have illustrated two embodiments thereof in the accompanying drawing. It is to be understood, however, that the invention is capable of additional embodiments, and that the device illustrated is susceptible of modification in certain respects, without departure from the scope of the appended claims.

In the drawing,

30 Figure 1 is a top view of a flush switch device.

Fig. 2 is a sectional view thereof.

Fig. 3 is a sectional view on line 3—3 of Fig. 2 showing the movable parts of the 35 switch mechanism.

Figs. 4 and 5 are similar views showing the parts when moved,

Fig. 6 is a sectional view on the lines 6—6 of Fig. 1.

40 Fig. 7 is a detailed perspective of a terminal contact.

Fig. 8 is a sectional view of a modified form of the switch mechanism, and,

45 Figs. 9 and 10 are sectional views on the line 9—9 of Fig. 8 showing the movable parts of the mechanism.

The switch mechanism illustrated comprises, in general, an oscillating contactor adapted to open and close circuit between 50 stationary contacts and inherently co-acting with such contacts to resist movement until energy is stored in a resilient device for imparting a snap movement to the contactor when one of a pair of operating push buttons approaches its limit of depression.

Referring more specifically to the mechanism shown in Sheet 1 of the drawings, a block 1 of insulation is mounted to rock on a central spindle 2 supported in uprights 3 of a skeleton frame 4. The ends of the 60 block are curvilinear and concentric with the spindle. At diagonally opposite corners, that is at points transversely aligned with the spindle 2, the block is provided with peripheral grooves 5 and at the other 65 corners with similar grooves 6. Conducting bands 7 are seated in one set of the grooves, *e. g.*, the groove 6.

Two pairs of stationary contacts 8 and 9 are mounted at opposite ends of the block 70 and are provided with spaced, resilient, curved extremities 10 arranged to rest within the grooves 5 in one position of the block, *i. e.*, when circuit is open, and to rest within the other grooves and on the bands 7 75 when the block is rocked to opposite position whereby circuit is completed across the contacts 8 by one of the bands 7, and across the other contacts 9 by the other band. It is to be noted also that the resilient contacts, while positioned, in the opposite grooves, act to yieldably restrain the block against movement, and this releasable lock is utilized to hold the contactor against rocking until sufficient energy is stored in an 80 operative connection with the push buttons to effect a snap movement of the block, as will appear hereinafter.

The operating members of the switch comprise a pair of plates 11 having push 90 buttons 12 and 13 at their upper ends which protrude through suitable openings in the frame 4 and an ornamental face plate 14. The plates 11 are disposed on opposite sides of the block and are provided with slots 15 95 through which the spindle 2 extends and, with ears 16 taking into guiding slots 17 in the uprights 3. Each plate is also provided with a lateral offset having an open transverse slot 18.

The operative connection between the push buttons and the contactor, referred to above, includes a coil spring 19 positioned through the block 1 with its ends 20 and 21 on opposite sides thereof and a pair of short 105 rocking levers 22 (shown in Figs. 1 and 2) suitably locked or keyed to the spindle 2. Each of these levers has a lost motion connection at one end with an operating plate 11 and a loose engagement at the other end 110

with an extremity of the coil spring. The lost motion connection just mentioned comprises studs 23 on the levers fitting within the slots 18 of the plates.

5 Four stationary contacts (one of which is shown in perspective in Fig. 7) are mounted in the corners of a rectangular chamber of a suitable insulating receptacle 24. Each of the contacts carries a binding post disposed adjacent a conductor aperture in the receptacle.

Assuming the push button 12 to be in elevated position and the circuit broken, as is represented in Fig. 3, depression of the 15 push button effects the following operation: The contiguous lever 22 is rocked, with the spindle 2 as its axis, so that the opposite end of the lever raises the end 20 of the spring. At the same time, the rotation of 20 the spindle is transmitted to the other rocking lever which turns and raises the opposite push button 13. The other end of the coil spring is restrained against movement, however, by engagement with a stud 25 provided on the side of the block. The latter is itself held against rotation by the resilient interlock of the stationary contacts which rest within the grooves 5 as above set forth. 25 As depression of the push button is continued, the spring is tensioned until the rising end thereof abuts a stud 26 located on the side of the block, whereupon a direct connection is established between the push button and the contact member so that positive movement is transmitted to the latter for overcoming the resilient restraint of the contacts. The energy stored in the spring 30 19 then snaps the block to opposite extreme position. In this position the resilient contacts 10 rest on the conducting bands 7 and circuit is accordingly closed. Pressure on the push button 13, however, will effect a snap movement of the contactor in an opposite direction through the operation of the 35 parts working reversely, it being understood that studs 25 and 26 are provided on both sides of the block.

In order to reduce liability of arcing between the stationary contacts, the ends of the 40 block are provided with medial raised portions 27 constituting an insulating barrier between the resilient extremities of the respective pairs of contacts. It is to be noted also that the opposite reciprocation of the 45 push buttons is effected by the parts which accomplish other functions as well, so that the construction of the device is simplified. Moreover, the location of the spring 19 eccentric to its axis enables easy assembly 50 of the parts and insures a maximum tensioning of the spring by a maximum leverage so that the force required to operate the device is relatively small and the action of the mechanism is smooth.

55 Referring to the Sheet 2 of the drawings,

the switch mechanism illustrated is, in general, similar to that already described. In this embodiment, however, a lever 28 is provided to govern the opposite reciprocations of the push-buttons and two separate coil springs 29 and 30 are provided on opposite sides of the insulating block. Moreover, each spring is offset transversely with respect to the spindle 2 and has its end on opposite sides thereof and on opposite sides of offset studs 31 on the sliding plates 11. The stationary contacts of the mechanism and the other structural details remain similar to the form already described.

The block 1 is held against oscillation by the resilient interlock with stationary contacts seated in a pair of the peripheral grooves. Pressure on the push-button 12 causes the lower end of the spring 29 to be depressed by the offset 31 on the sliding plate 11 while the opposite end of the spring is held stationary by engagement with the spindle 2. At the same time the opposite push-button is raised and the spring 30 works in a similar manner, tending to throw the block 1 in the same rotative direction. A stud 32 is provided on each side of the block 1 for engagement with the depressed end of a spring as the corresponding push-button approaches its limit of travel. By this means a positive connection is established and movement is imparted to the block for overcoming the resilient lock thereof.

What I claim as new and desire to secure by Letters Patent is:—

1. In an electric flush switch, in combination, a pair of movable operating members, a contact member pivoted at right angles to the direction of movement of said operating members, an energy storing connection between said contact member and said operating members, restraining means for said contact member and means on said contact member to be positively actuated by said operating members for overcoming the restraint of said restraining means.

2. In an electric flush switch, in combination, a pair of spaced rectilinearly movable operating members, an oscillatory contact member therebetween and movable on an axis at right angles to the direction of movement thereof, an energy storing connection between said contact member and said operating members for exerting pressure on the former to move the same, and releasable restraining means for said contact member adapted to release the same at a predetermined pressure thereon.

3. In an electric flush switch, in combination, a rectilinearly movable operating member, a pivoted contact member and an energy storing operative connection between said members including a coil spring disposed parallel to the axis of said contact members but eccentric thereto.

4. In an electric switch, in combination, a rectilinearly movable operating member, a pivoted contact member, a coil spring having its axis disposed in a straight line parallel to the axis of said contact member but eccentric thereto, an operative connection between one end of said spring and said operating member, and an operative connection between the other end of said spring and said contact member, said connections effecting tensioning of said spring when said operating member is actuated, and means to restrain movement of said contact member while said spring is tensioned.
5. In an electric flush switch, in combination, a pair of spaced push button operating members, a contact member pivoted therebetween upon an axis at right angles to the direction of movement thereof, energy storing means including a coiled spring having its ends disposed on opposite sides of said contact member, an operative connection between each end of said spring and its adjacent operating member when the latter is moved in one direction, an operative connection between each end of said spring and the adjacent side of said block when said operating member is moved in an opposite direction and means to restrain movement of said contact member until energy is stored in said means.
6. In an electric flush switch, in combination, a pivoted insulating block having spaced peripheral grooves, a conducting band seated in one of said grooves, a pair of stationary contacts having spaced resilient extremities adapted to rest within either of said grooves in accordance with the position of said block, said block having a raised portion disposed between the extremities of said stationary contacts, and means for imparting a snap movement to said block for positioning the same to receive the extremities of said stationary contacts in either of said grooves.
7. In an electric switch, in combination, a push-button operating member, a pivoted contact member, a coil spring associated with said members, means to check movement of said contact member, a shoulder on said contact member for restraining an end of said spring, a shoulder on said operating member for moving the other end of said spring, and a second shoulder on said contact member to be engaged by said last mentioned end of said spring for establishing a direct connection with said operating member to overcome said means.
8. In an electric flush switch, in combination, a pair of push-button operating members, a pivoted contact member, a coil spring having ends on opposite sides of said contact member and adjacent said operating members, means to check movement of said contact member, a lug on each side of said contact member for restraining an end of said spring, a lug on each of said operating members for moving the unrestrained end of said spring, and a second lug on each side of said contact member to be engaged and moved by said last mentioned end of said spring after energy is stored in the latter.
- In witness whereof I have hereunto subscribed my name in the presence of two witnesses.
